UNITED STATES PATENT OFFICE.

WALTER A. FREDERICK, OF MUSKEGON, MICHIGAN.

BREATHER FOR EXPLOSIVE-ENGINES.

967,895.

Specification of Letters Patent. Patented Aug. 23, 1910.

Application filed April 29, 1910, Serial No. 558,392.

To all whom it may concern:

Be it known that I, WALTER A. FREDERICK, a citizen of the United States, residing at Muskegon, in the county of Muskegon and State of Michigan, have invented certain new and useful Improvements in Breathers for Explosive-Engines; and I do hereby declare the following to be a full, clear, and exact description of the invention, such as will enable others skilled in the art to which it appertains to make and use the same.

My invention has for its object to provide an improved breather and filling pipe for explosive engines, and to this end the invention consists of the novel devices and construction and arrangement of parts hereinafter described and defined in the claims.

Primarily, this device is intended to act as a vent to the crank case of an explosive engine, to thereby relieve the compression and allow the heat to escape and prevent the crank case from becoming overheated. Hitherto devices of this general character have been provided, but all thereof so far as I am aware, have been provided with screens to prevent the escape of oil, and these screens are liable to become stopped up and, furthermore, even when clean give a quite high resistance to the passage of gases and air and hence produce undesirable back pressure.

My invention provides a breather and filling tube, which requires no screen, but in lieu thereof, is provided with alternated or interlapping baffle plates or deflectors, which may be of various shape and arrangement, but are so disposed that they allow for the free passage of air and gases therethrough, but prevent oil from being splashed or thrown out of the crank case. The breathing tube may, also, be used as a place to introduce oil into the crank case.

In the accompanying drawings, which illustrate the invention, like characters indicate like parts throughout the several views.

Referring to the drawings: Figure 1 is a view chiefly in vertical section, showing the improved breather and filling tube, some parts thereof being shown in full; Fig. 2 is a section taken on the line $x^2 x^2$ of Fig. 1.

The tubular body of the breather is indicated by the numeral 1 and the upper end thereof is preferably made bell-shaped or flaring at 2, while the lower end thereof, as shown, is slightly contracted and externally threaded at 3 to adapt it to be screwed into the engine crank case. Within the tube 1 is a multiplicity of alternated and interlapped baffle plates or deflecting flanges 4 preferably, although not necessarily, integral with the said tube. These baffle plates or deflectors are downwardly inclined toward their edges, so that any oil which may lodge thereon will be directed downward into the crank case. The uppermost baffle plate or flange 4 is provided with an upright sleeve 5 located at the axis of the tube 1.

The numeral 6 indicates a deflecting cap 70 shown as secured to the upper end of a stem 7, the lower end of which is split and is frictionally engaged with the sleeve 5. When the cap 6 is thus positioned, its edge stands clear of the upper edge of the tube so as to leave a continuous annular discharge passage 8.

The efficiency of the device above described has been demonstrated in practice.

What I claim is:

1. A breathing tube for an engine crank case, provided with interior alternated and interlapped baffle plates, forming a free but zigzag air passage through the said tube and a cap supported with its edge spaced from the upper edge of said tube, substantially as described.

2. A breathing tube for an engine crank case, provided with alternated and interlapped inclined baffle plates, the upper baffle 90 plate having a sleeve at the axis of said tube and a cap provided with a stem engaging said sleeve, the edge of said cap being spaced from the upper edge of said tube, substantially as described.

In testimony whereof I affix my signature in presence of two witnesses.

WALTER A. FREDERICK.
